UNITED STATES PATENT OFFICE.

VICTOR A. STEINER, OF BRIDGEPORT, CONNECTICUT, ASSIGNOR TO GROSS AND STEINER, OF BRIDGEPORT, CONNECTICUT, A COPARTNERSHIP CONSISTING OF CARL W. GROSS AND VICTOR A. STEINER.

CAN OPENER.

Application filed January 12, 1922. Serial No. 528,676.

To all whom it may concern:

Be it known that VICTOR A. STEINER, a citizen of the United States, and resident of Bridgeport, in the county of Fairfield and State of Connecticut, has invented certain new and useful Improvements in Can Openers, of which the following is a specification.

This invention relates to an improved can opener of the type adapted to remove an end from the body portion of a can by cutting through the wall of the can adjacent to the end to be removed.

The invention has for its principal object to provide a novel device of the present character, of simple construction and consisting of few parts, which can be fastened upon a support to be quickly and easily manipulable by use of one hand, the operator's other hand being free to grasp the can when the novel device shall have performed its work.

A further important object is to provide a can opener equipped with a feeding roller adapted to engage a side of the flange of a can, with a rotatable gripping roller adapted to be clamped against the side of the flange in opposed relation to the feeding roller, with a circular, preferably square faced, cutter adapted to pierce the wall of the can adjacent the flange when the feeding and gripping rollers are clamped against the flange, and with mechanism whereby the rollers may be so clamped and one of the rollers may be rotated to advance the can against the cutting edge of the circular cutter in order that said cutting edge may continuously cut through the can wall for its full circumference.

A still further important object is to provide in the device a rotatable gripping roller that will be normally free to move from and toward the feeding roller, and to so construct and arrange the rotatable gripping roller and the mechanism for rotating the feeding roller that said mechanism can be readily manipulated to remove the rotatable gripping roller from the flange of the can when this is desirable, as well as to clamp the gripping roller against said flange.

Still further important objects are to provide in the device a circular cutter having a square faced cutting edge adapted to evenly

break the metal of a can and to prevent the formation of splinters or chips on the can, this occurring frequently when a beveled edge cutter is employed to remove the ends of cans and the splinters or chips being liable to cause injuries to the hands of operators; to so construct the square faced cutter that it will act as a traveler to assist in feeding the can forwardly; and to so construct the device that the tension between the cutter and roller opposed thereto can be relieved, whereby an easier and more positive operation of the can opener is effected.

With the above objects in view as well as others which will appear as the specification proceeds the invention comprises the construction, arrangement and combination of parts as now to be fully described and as hereinafter to be specifically claimed, it being understood that the disclosure herein is merely illustrative and meant to in no way limit the spirit of invention, changes in details of construction and arrangement of parts being permissible so long as within the scope of the appended claims.

In the accompanying drawing forming a part of this specification,

Fig. 1 is a top plan view of the can opener as in use, showing the rotatable gripping roller spaced from the feeding roller to allow insertion of a can;

Fig. 2 is a top plan view corresponding with the showing of Fig. 1, but disclosing the rotatable gripping roller located closely adjacent the feeding roller to grip a can;

Fig. 3 is an elevational view of the device and its support, partially in section; and

Fig. 4 is an enlarged detail elevational view of the feeding roller, the gripping roller, the circular, square faced cutter, and the squared shaft supporting the feeding roller and cutter.

Referring to drawing, 10 denotes the body of a plate adapted to be fastened upon a support A in some suitable manner, as by means of an ordinary clamp B, 11 denotes a neck upon said body which is offset at its outer end as at 12, and 13 denotes a head carried by said neck and desirably parallel with said body.

Numeral 14 denotes a link pivoted upon the head 13 as at 15 and in alignment with the body 10 of the plate. The edge 16 of the link 14, spaced from the pivot 15, is of

general curved conformation to freely slide over the edge 17 of the body 10 when the link 14 is swung on its pivot 15. Numeral 18 denotes a pin mounted in the link 14 adjacent its edge 16 and carrying a pair of washers, denoted by 19 and 20 respectively the washer 19 being arranged preferably closely adjacent to or contiguous with the upper face of the body 10 and the washer 20 being arranged preferably closely adjacent to or contiguous with the bottom face thereof to constitute the rotatable gripping roller of the can opener, in such manner that said washers can rotate with or on the pin 18. As will be noted, the pivot for these washers is arranged at a distance from the edge 16 which is less than one-half the diameter of each washer with the result that portions of said washers overlap the edge 17 of the body 10, whereby the aligning position of the link with the body of the plate is assured. The head 13 of the plate is extended, as at 21, for a slight distance in the direction of the body 10 to limit the movement of the link 14 when swung on its pivot 15 away from the neck 11, the extension 21, obviously, serving as a stop for the washer 19.

Numeral 22 denotes an opening in the body 10 of the plate adjacent the edge 17 thereof, 23 a round washer desirably of the thickness of said body and arranged to state in the opening, 24 a squared shaft in a similarly shaped hole in the washer 23 and extending to the opposite sides thereof, 25 a larger washer upon the upper end of the squared shaft and preferably arranged contiguous with the washer 23, and the upper face of the body 10, 26 a lever upon said shaft and above the washer 25, 27 a manipulating handle upon the lever, 28 a lug struck downwardly from the lever for a purpose to be explained, 29 a spacing washer upon the lower extension of the shaft 24 and preferably contiguous with the bottom face of the plate 10, 30 the feeding roller of the can opener on the squared shaft beneath the spacing washer 29 and contiguous therewith, 31 a second spacing washer beneath and contiguous with the feeding roller, 32 a circular, square faced cutter contiguous with the washer 31, and 33 represents a supporting washer for the circular cutter. Evidently, when the manipulating handle 27 is moved to turn the lever 26, the several washers, the feeding roller and the circular cutter will turn as a unit with the washer 23 in the body 10.

The arrangement as described makes provisions whereby the feeding roller and gripping roller can lie in the same horizontal plane to grip opposite sides of the flange of a can, denoted C, and the circular cutter can be situated to engage the wall of the can below and closely adjacent to its flange. 65 The feeding roller has a preferably serrated

edge and the cutting edge of the circular cutter can be of any suitable conformation, although it is desirably of some width to break the tin of the can and is provided with a toothed edge 34. 70

The device operates in the following manner. When it is desired to open a can, the rotatable gripping roller is moved away from the feeding roller to be situated as shown in Fig. 1, and an end of the can is positioned against the bottom face of the body 10 of the plate so that the flange of the can is between and adjacent to the feeding and gripping rollers. The operating lever is rotated, in the direction of the arrows 75 Figs. 1 and 2, until the end of the can is removed. Referring more particularly to Figs. 1 and 2, it will be seen that upon the initial rotation of the operating lever, the lug 28 rides against the washer 19 and moves the link 14 into engagement with the neck 11, positioning the rotatable gripping roller 20 closely adjacent to the feeding roller 30 to cause the square faced cutting edge 34 of the circular cutter to pierce the 80 can and the gripping roller and feeding roller to be clamped against the sides of the flange of the can in opposed relation to each other. Continued rotation of the operating lever and feeding roller, obviously, will rotate the circular cutter as well as the gripping roller, and will feed the can forwardly against the square faced edge of the circular cutter. It will be evident that the link 14 can not at this time be swung on its pivot 85 away from the neck 11, for the reason that the rotating force exerted against the gripping roller and the can by both the feeding roller and the circular cutter is in the direction toward said neck. When the end of the 90 can has been removed from the body portion thereof, the flange can be released from the roller by simply reversely turning the operating lever for a short distance. The effect of the reverse turn is to cause the 95 feeding roller, as well as the circular cutter, to feed the flange backwardly against the gripping roller to force the link 14 to swing on its pivot away from the neck 11 and the rotatable gripping roller to move away from the feeding roller to allow a different can to be opened in the manner already fully set forth. It is apparent that the arrangement of the circular cutter can be reversed. That is to say, said cutter can be arranged upon 100 the pin 18 beneath the gripping roller 20. This would reverse the arrangement of the flange between the feeding and gripping rollers. 110

Attention is called to the fact that the 125 square faced cutting edge 34 of the circular cutter has some width and breaks the tin of a can making a kerf thereabout, so that when an end of a can is cut off there can be no resulting splinter or chip, the thickness of 130

said cutting edge caring for slight inaccuracies in traversing the circumferences of cans and insuring that the cutter will make a continuous, even cut, returning to its exact 5 starting point, as will be understood.

The neck 11 of the plate allows a slight resiliency between the head 13 and the feeding roller 30 which aids towards an easier and more positive operation of the can 10 opener, this resiliency relieving the tension between the rotatable gripping roller and the circular cutter tending to bind the can.

The use of the squared shaft 24 permits the employment of a circular cutter and 15 feeding roller of diameters sufficiently small to insure that the can opener can be operated with a minimum of effort.

It is to be remarked that the device as hereinbefore fully described and illustrated 20 is capable of opening cans of any cross sectional configuration.

Having thus fully described the invention what I claim as new and desire to secure by Letters Patent is:

25 1. In a can opener, a rotatable feeding roller, a rotatable gripping roller, a cutter, a member for rotating one of said rollers, and means actuated by said member for moving the rollers toward each other.

30 2. In a can opener, a rotatable feeding roller, a rotatable gripping roller, a circular cutter, a member for rotating one of said rollers and said cutter, and means actuated by said member for moving said rollers toward each other.

35 3. In a can opener, a rotatable feeding roller, a rotatable gripping roller, a cutter mounted to turn with one of said rollers, a member for rotating one of said rollers and 40 said cutter, and means actuated by said member for moving said rollers toward each other.

45 4. In a can opener, a rotatable feeding roller, a rotatable gripping roller, a cutter mounted to turn with one of said rollers, means for rotating one of said rollers, and a device upon said means and actuated thereby for engaging one of said rollers to move the same toward the other roller.

50 5. In a can opener, a rotatable feeding roller, a rotatable gripping roller, a cutter, a member for rotating one of said rollers, and means actuated by said member for moving the rollers toward and from each other.

55 6. In a can opener, a rotatable feeding roller, a rotatable gripping roller, a circular cutter, a member for rotating one of said rollers and said cutter, and means actuated by said member for moving said rollers toward and from each other.

60 7. In a can opener, a rotatable feeding roller, a rotatable gripping roller, a cutter mounted to turn with one of said rollers, a member for rotating one of said rollers, a

device associated with said member and adapted to engage one of said rollers to move the same toward the other of said rollers when the member is rotated to feed a can, and means whereby the rollers can 70 be moved apart by rotation of the member in opposite direction.

8. In a can opener, a rotatable feeding roller, a rotatable gripping roller, a cutter, a member for rotating one of said rollers, 75 a device associated with said member and adapted to engage one of said rollers when the member is rotated to feed a can, and means whereby the rollers can be moved apart by rotation of the member in opposite direction. 80

9. In a can opener, a feeding roller adapted to engage one side of a flange of a can, a rotatable gripping roller adapted to have movement toward and from the feeding 85 roller and to engage the opposite side of said flange in opposed relation to said feeding roller, a cutter having an edge adapted to enter the wall of a can adjacent said flange when the rollers are moved into engagement with the flange, a member for rotating the feeding roller, and a device actuated by said member for engaging the gripping roller to move it against the flange, whereby when said feeding roller is rotated said can will be fed forwardly against 90 said cutting edge. 95

10. In a can opener, means for rotating a can to be cut, and a cutter having a relatively broad square face for traversing the 100 circumference of the can to break the metal thereof, whereby slight inaccuracies can be cared for and the cutter face can return to its exact starting point at the finish of an operation of removing an end of a can. 105

11. In a can opener, a plate consisting of a body, a head and a neck connecting said body and head, a roller supported on said body, a roller supported from said head, said rollers adapted to grip the sides 110 of the flange of a can in opposed relation to each other, and a cutter associated with one of said rollers, said neck constituting a resilient connection between said body and head. 115

12. In a can opener, a plate consisting of a body, a head and a neck connecting said body and head, a roller supported on said body, a link pivoted on said head, a roller pivoted on said link and adapted to move 120 with said link toward and from said roller on said body, said rollers adapted to grip the sides of the flange of a can in opposed relation to each other, and a cutter associated with one of said rollers and adapted 125 to pierce the wall of said can adjacent said flange, said neck constituting a resilient connection between said body and said head relieving tension between said cutter and can tending to bind said can. 130

13. A combination as recited in claim 12,
wherein the link pivotally supports a washer
arranged to engage an extension on said
head to limit the extent to which the link
5 can swing on its pivot away from the neck.
14. In a can opener, a plate, a round
washer mounted to rotate therein, a squared
shaft in said washer and extending above
and below said plate, a feeding roller and
10 a rotatable cutter on said shaft and beneath

said plate, washers spacing said roller from
said plate and said cutter from said roller,
a washer upon said shaft and above said
plate, and a member fixed upon said shaft
whereby the same can be rotated.

15

Signed at Bridgeport, in the county of
Fairfield and State of Connecticut, this 7th
day of January, A. D. 1922.

VICTOR A. STEINER.
